UNITED STATES PATENT OFFICE.

JAMES H. LOCKETT, OF OAKLAND, CALIFORNIA.

WHEEL.

Application filed May 29, 1922. Serial No. 564,399.

To all whom it may concern:

Be it known that I, JAMES H. LOCKETT, a citizen of the United States, and a resident of Oakland, county of Alameda, and 5 State of California, have invented a new and useful Wheel, of which the following is a specification.

The present invention relates to improvements in wheels and has particular reference to means for cushioning the same. The principal object of the invention is to introduce shock absorbing or cushioning means between the rim and the hub of the wheel in such a manner that the cushioning means 15 as such does not make contact with the road bed or the rail on which the vehicle travels but is interposed between the rim and the hub in such a manner as to be covered altogether by the supporting structure. A 20 further object of the invention is to provide a plurality of cushioning members co-operating with each other in such a manner that each of them will support the load independently of the other in case the latter 25 becomes damaged which feature also allows of the removal and the replacing of one cushioning member while the full load rests on the wheel. It is further proposed to provide a construction that will not allow of 30 a complete collapse of the wheel even though all the cushioning members should collapse. Further objects and advantages will appear as the description of my device proceeds.

The preferred forms of my invention are 35 illustrated in the accompanying drawing in which Figure 1 shows a side elevation of the wheel of a railroad car having my cushioning means attached thereto, a portion being broken away; Figure 2, an end view 40 of the same partly shown in section; Figure 3, a side elevation of a truck wheel having my cushioning means attached thereto; Figure 4, a side elevation of the same partly in section and Figure 5 a detail view showing the surface of one of the members engaging the cushioning means. While I have shown only the preferred forms of the invention I wish to have it understood that various changes or modifications may be 45 made within the scope of the claims hereto attached without departing from the spirit 50 of the invention.

The axle (1) has the hub (2) supported thereon. For the purposes of this invention 55 it does not make any difference whether

the hub rotates on the axle or is keyed to the same and driven by it. The hub is provided with a peripheral flange (3) to which are secured on opposite sides the disks (4) and (6) by any suitable means as for instance 60 by the bolts (7) and the nuts (8), retaining rings (9) being interposed between the plates and the holding members of the bolts. The two plates are held in spaced relation to each other by means of the rings (11) and (12) secured by suitable bolts (13). The plates which are disc-shaped terminate at their outer periphery in webs (14) and (16) adapted to receive and to surround the inner circumferential portion of the cushioning member (17) which is shown in the drawing as an inflated pneumatic tire but which may be replaced by any other suitable cushioning means. The rim (18) of the wheel has an internal flange (19) extending therefrom, the inner edge of which is received between the two plates (4) and (6) and holds the rim in vertical alinement with the plates. The flange (19) is also provided with webs (21) and (22) extending from opposite sides of the flange and curved in cross section so as to snugly fit over the outer circumference of the cushioning means. As shown in Figure 2 the webs are preferably arranged in such a manner 70 that each two co-operate in completely surrounding the cushioning means while not interfering with the radial motion of the flange (19) and the rim relative to the plates (4) and (6) and the hub, the latter motion 75 being completely controlled by the cushioning means. 80

If the wheel is to be driven from the axle and to impart motion to the vehicle I preferably use corrugated surfaces for engagement between the various webs mentioned and the cushioning means so as to increase friction between the same and to render the friction more intensive than that between the rim and the rail or road bed on which 90 the vehicle travels. One of these corrugated surfaces (23) is illustrated in Figure 5, but it will be understood that various other means may be used for increasing friction between the webs and the cushioning 95 member. 100

It will be noticed that the outer one (12) of the spacing rings is disposed rather close to the inner periphery of the flange (19) so as to allow a limited play of the latter 110

only. By this arrangement a complete collapse of the wheel is prevented even if the cushioning members should fail.

The advantages of my wheel will be readily understood from the foregoing description. The construction is perfectly rigid as far as lateral motion is concerned and will withstand any lateral pressure that a rigid wheel of similar size and similar weight would resist. Radially it is allowed to yield to shocks practically to the same extent as an inflated automobile tire and it is not dependent in its operation on both of the cushioning members since even if one of them should collapse, the other one will maintain the load due to the fact that lateral displacement of the rim relative to the guide plates (4) and (6) is prevented. This feature also allows of the removal and replacement of one of the cushioning means without relieving the wheel of the pressure of the load. The fact that the inflated tires or other cushioning means are surrounded completely by the supporting structure eliminates rapid deterioration of the cushion, due to exposure to the elements and abrasion due to frictional contact with the road surface.

The form shown in Figures 3 and 4 differs substantially only in the form of the rim. The rim of Figure 2 is adapted to be used for railroad cars while the rim (24) of Figure 4 is designed to be used for motor trucks or other vehicles engaging the road bed and is preferably provided with an additional solid cushioning member (26) on its outer periphery.

I claim:

- 40 1. In a wheel, a hub, a rim having an internal flange thereon, guide means radiating from the hub slidably engaging the flange for maintaining the rim in vertical alinement, and cushioning means interposed between the rim and the hub.
- 45 2. In a wheel, a hub, a rim having an internal flange thereon, guide means radiating from the hub engaging the flange for maintaining the rim in vertical alinement, and cushioning means interposed between the rim and the hub on opposite sides of the flange.
- 50 3. In a wheel, a hub, a rim having an internal flange thereon, guide means radiating from the hub engaging the flange for maintaining the rim in vertical alinement, and pneumatic cushioning tubes interposed be-

tween the rim and the hub on opposite sides of the flange.

4. In a wheel, a hub, a rim having an internal flange thereon with lateral webs extending from its sides, vertical guide members for the flange extending from the hub engaging the flange on opposite sides and terminating in lateral webs registering with the webs of the flange and cushioning means interposed between the webs on opposite sides of the flange.

5. In a wheel, a hub, a rim having an internal flange thereon with lateral webs extending from its sides, vertical guide members for the flange extending from the hub engaging the flange on opposite sides and terminating in lateral webs registering with the webs of the flange and cushioning means interposed between the webs on opposite sides of the flange, the webs being curved in cross-section so as to substantially enclose the cushioning means.

6. In a wheel, a hub, a rim having an internal flange thereon with lateral webs extending from its sides, vertical guide members for the flange extending from the hub engaging the flange on opposite sides and terminating in lateral webs registering with the webs of the flange and cushioning means interposed between the webs on opposite sides of the flange, the webs being curved in cross-section so as to substantially enclose the cushioning means and having means associated therewith for preventing the cushioning means from sliding peripherally.

7. In a wheel, a hub, a rim having an internal flange thereon, guide plates extending from the hub in spaced and parallel relation engaging the flange on opposite sides, lateral webs extending from opposite sides of the flange and from the guide plates in opposing relation, and cushioning means interposed between the webs on opposite sides of the flange.

8. In a wheel, a hub, a rim having an internal flange thereon; guide plates extending from the hub in spaced and parallel relation engaging the flange on opposite sides, lateral webs extending from opposite sides of the flange and from the guide plates in opposing relation, and cushioning means interposed between the webs on opposite sides of the flange, the webs being curved in cross-section so as to substantially enclose the cushioning means.

JAMES H. LOCKETT.
